ELECTRIC SWITCH

Thomas L. Parker, Chicago, Ill., assignor to
Paragon Electric Mfg. Co., not Incorporated

Application June 17, 1933, Serial No. 676,296

4 Claims. (Cl. 200—11)

This invention relates to switches, and particularly to a switch whereby a plurality of circuit connections may be established for controlling the operation of a heating element, such, for example, as an electric heating pad, or the like.

One object of the present invention is to provide a switch which is convenient to operate, and which is constructed to insure proper positioning of the various elements embodied in the construction.

Another object of the invention is to provide novel and efficient means for yieldingly securing the relatively movable contacts against accidental displacement with respect to the stationary contacts.

A further object of the invention is to provide a structure wherein the movable contacts are combined in an integral unitary structure to insure maintaining their proper efficient relationship at all times.

A still further object of the invention is to improve devices of the character described in sundry details hereinafter referred to and particularly pointed out in the appended claims.

One embodiment of the present invention is shown for illustrative purposes in the accompanying drawing, in which

Fig. 1 is a face view of a switch housing embodying features of the present invention and taken from the operating side thereof;

Fig. 2 is a plan section taken substantially as indicated by the line 2—2 of Fig. 3;

Fig. 3 is a transverse sectional elevation taken substantially as indicated by the line 3—3 of Figs. 1 and 2;

Fig. 4 is a detailed elevational view of a through connection employed in the illustrative embodiment of the present invention; and

Fig. 5 is a perspective view of a movable contact element employed in the present structure.

As shown in the drawing, the housing of the present invention, indicated as a whole by the numeral 5, comprises bottom and top members or portions 6 and 7, respectively, adapted to be secured together by means of screws 8 and 9, or other suitable means, and rigidly mounted in the bottom member 6 is a stationary contact 11 and a through connection 12 of current conducting material having binding posts 13 and 14, respectively, by which the contact 11 and through connection 12 may be connected to a suitable source of current supply through line conductors 15 and 16, respectively.

Mounted also in the bottom member 6 are a pair of stationary contacts 17 and 18 annularly

spaced with reference to each other and to the contact 11, the contacts 17 and 18 and the opposite end of the through connection 12 being provided with binding screws 19, 21 and 22, respectively, by which connection may be made with wires 23, 24 and 25, respectively, of a heating unit such as an electric pad, or the like. The adjacent inner ends of the stationary contacts 11, 17 and 18 are shown in the present instance as imbedded in the material of the bottom member 6 and adapted to be engaged by a plurality of movable contacts 26, 27 and 28 formed on a movable contact element indicated as a whole by the numeral 29 for establishing a plurality of circuit connections within the housing 5 to obtain various degrees of heat in a heating element controlled by the switch.

For supporting the movable contact element 29 and controlling the position of the movable contacts 26, 27 and 28, a movable contact carrier, indicated as a whole by the numeral 31, is rotatably mounted in an aperture 32 formed in the top member 7, and is provided with a centrally disposed axial recess 33 forming a downwardly extending annular flange 34 having annularly spaced notches 35 formed therein adapted to receive the contacts 26, 27 and 28 respectively, with the central or body portion of the movable contact element 29 positioned in the recess 33, the movable contacts 26, 27 and 28 overlying the stationary contacts 11, 17 and 18, and adapted to be brought into engagement therewith when the carrier 31 is rotated. For manually rotating the carrier 31, an actuating member, indicated as a whole by the numeral 36, is positioned outside the housing on the upper side thereof and provided with an elongated projection 37 adapted to engage an elongated recess 38 formed in the upper end of the carrier 31 in a manner to secure the carrier 31 and actuating member 36 against relative angular movement, the carrier and actuating member being secured against axial movement with respect to each other by means of a bolt 39 passing through apertures 41 and 42 formed in the movable contact element 29 and the carrier 31, respectively, and being screw threaded into the actuating member 36, the carrier 31 and actuating member 36 being free to rotate together in the aperture 32 and secured against axial movement with respect to the housing by shoulders 43 and 44 formed on the top housing member 7.

Positioned in the recess 33 and surrounding the bolt 39 between the movable contact element 29 and carrier 31 is a spring 45 adapted to yield-

ingly urge the movable contacts 26, 27 and 28 mounted in the carrier 31 into engagement with the stationary contacts 11, 17 and 18 mounted in the bottom member 6 of the housing.

5 For conveniently rotating the actuating member 36, a plurality of radially extending ribs 46 are formed on the outer or top surface of the actuating member, one of the ribs 46 being provided with an indicator 47 adapted to be brought into registry with the indicia "Off", "High", 10 "Med." and "Low" to indicate the proper connections between the movable contacts 26, 27 and 28 with the stationary contacts 11, 17 and 18 for obtaining the degree of heat desired in 15 the heating element such as an electric pad, or the like.

For yieldingly securing the carrier 31 against accidental rotary movement, and for maintaining the movable contacts in proper alignment with the stationary contacts, yieldable means 20 shown, in the present instance, as a resilient flat spring pawl 48 is mounted adjacent one of its ends in a notch or recess 49 formed in the carrier 31, and having a detent 51 formed at its opposite or free end adapted to engage annularly spaced grooves 52 formed in the carrier adjacent the recess 32.

It will be observed that by such an arrangement the carrier 31 and movable contacts 26, 27 and 30 28 will be yieldingly secured against accidental rotary movement, and that when manual force is exerted against the ribs 46 to rotate the carrier, the spring pawl 48 will yield as the detent 51 is forced out of one of the grooves 52 and into an 35 annular recess 53 formed in the carrier 31, and when the carrier has been rotated to establish a new relationship of the movable and stationary contacts, the detent 51 will drop into the next groove 52, thereby yieldingly maintaining the movable and stationary contacts in proper alignment.

For insuring proper positioning of the top housing member 1 with relation to the bottom member 6, the through connection 12 is provided, 45 in the present instance, with a plurality of offset portions 54 extending above and beyond the dividing line between the portions 6 and 1 of the housing, and into the top portion thereof, and formed in the top portion 1 are a plurality of inwardly extending ribs 55 positioned transversely opposite the offset portions 54 of the through connection 12. Thus, it will be observed that interference between the offset portions 54 and ribs 55 will be encountered unless 50 the top portion 1 of the housing and the bottom portion 6 are assembled in a manner to position the ribs 55 at the opposite side of the housing from the offset portion 54 as illustrated in Fig. 1.

It will be observed from the foregoing description that the present invention provides a novel construction and arrangement of movable and stationary contacts by which a plurality of circuit connections may be established within a housing for controlling the degree of heat desired in a heating pad, or the like, that suitable and efficient means are provided for yieldingly maintaining the contacts in proper alignment, and that suitable means are provided for insuring the proper relative positioning of the bottom and top portions of the housing and the respective contacts mounted therein.

Obviously, the present invention is not limited to the precise construction and arrangement shown and described as the same may be variously modified. Moreover, all the features of the

invention need not be used conjointly as the same may be used to advantage in variously different combinations and sub-combinations.

What I claim as new and desire to cover by Letters Patent is:

1. In an electric switch, the combination of a split housing comprising bottom and top portions of insulating material, a plurality of annularly spaced relatively stationary contacts mounted in said bottom portion, a carrier rotatably mounted in said top portion, a plurality of connected radially extending movable contacts mounted in and bodily movable with respect to said carrier and engageable with said stationary contacts, means for yieldingly urging said movable contacts toward the stationary contacts, an actuating member outside said housing rigidly connected to said carrier and rotatable therewith, and yieldable means mounted on said carrier and engageable with said top portion for yieldingly maintaining the carrier in a plurality of relatively fixed positions with respect to said top portion and maintaining the movable contacts in alignment with said stationary contacts.

2. In an electric switch, the combination of a 25 split housing comprising connected bottom and top portions of insulating material, a plurality of annularly spaced relatively stationary contacts mounted in said bottom portion, said top portion having an aperture formed therein and a plurality of annularly spaced grooves adjacent said aperture, a carrier rotatably mounted in said aperture, a downwardly extending annular flange on said carrier having a plurality of annularly spaced notches formed therein, a plurality of connected radially extending contacts mounted in said notches and bodily movable with respect to said carrier and engageable with said stationary contacts, resilient means mounted in said carrier for urging the movable contacts toward said stationary contacts, an actuating member outside said housing rigidly connected to said carrier, and a resilient pawl mounted in said carrier and having a free end portion adapted to engage the grooves in the top member adjacent the aperture formed therein for yieldably maintaining the carrier in a plurality of positions with respect to the top portion, and maintaining the movable contacts in alignment with the stationary contacts for establishing a plurality of circuit connections within the housing.

3. In an electric switch, the combination of a split housing comprising bottom and top portions, fastening means operatively related to the respective portions for securing the portions together, a plurality of annularly spaced relatively stationary contacts and a through connection having binding screws associated therewith mounted in said bottom portion, said through connection having an offset portion formed thereon and extending beyond the dividing line between the portions of the housing and into the top portion thereof, an inwardly extending rib formed on the top portion on the opposite side of the housing from said offset portion of the through connection and engageable therewith when said top and bottom portions of the housing are arranged in improper relationship, a carrier rotatably mounted on said top portion, a plurality of connected movable contacts mounted in said carrier and engageable with said stationary contacts, an actuating member outside said housing rigidly connected to said carrier and rotatable therewith, and yieldable means operatively related to said carrier and top portion for yieldingly maintaining the carrier in

a plurality of positions with respect to said top portion and maintaining the movable contacts in alignment with the respective stationary contacts for establishing a plurality of circuit connections 5 within the housing.

4. In an electric switch, the combination of a split housing comprising bottom and top portions, fastening means operatively related to the respective portions for securing the portions together, 10 a plurality of annularly spaced relatively stationary contacts and a through connection having binding screws associated therewith mounted in said bottom portion, said through connection having a plurality of offset portions formed thereon 15 and extending beyond the dividing line between the portions of the housing and into the top portion thereof, a plurality of inwardly extending ribs formed on the top portion transversely opposite the offset portions of the through connection 20 and engageable therewith when said top and bot-

tom portions of the housing are arranged in improper relationship, a carrier having an elongated depression formed therein rotatably mounted in said top portion, a plurality of connected radially extending movable contacts mounted in and rotatable with said carrier and engageable with said stationary contacts, an actuating member outside said housing having an elongated projection positioned in said depression, means for rigidly connecting said carrier and actuating member together, and yieldable means mounted on said carrier and engageable with said top portion for yieldingly maintaining the carrier in a plurality of positions with respect to the top portion and maintaining the movable contacts in alignment 15 with the respective stationary contacts for establishing a plurality of circuit connections within the housing. 5

THOMAS L. PARKER.
